(57) **CLAIM**

The ornamental design for an electronic device, as shown in the accompanying drawings and described above.

DESCRIPTION

FIG. 1 is a top front perspective view of an electronic device with its unclaimed cable in a stowed configuration, in accordance with the present invention.

FIG. 2 is a top rear perspective view of the configuration of FIG. 1.

FIG. 3 is another top front perspective view of the configuration of FIG. 1.

FIG. 4 is a bottom front perspective view of the configuration of FIG. 1.

FIG. 5 is a bottom rear perspective view of the configuration of FIG. 1.

FIG. 6 is a top plan view of the configuration of FIG. 1.

FIG. 7 is a bottom plan view of the configuration of FIG. 1.

FIG. 8 is a front elevation view of the configuration of FIG. 1.

FIG. 9 is a rear elevation view of the configuration of FIG. 1.

FIG. 10 is right elevation view of the configuration of FIG. 1.

FIG. 11 is left elevation view of the configuration of FIG. 1.

FIG. 12 is a top front perspective view of the electronic device of FIG. 1 with its unclaimed cable in an extended configuration, in accordance with the present invention.

FIG. 13 is a top rear perspective view of the configuration of FIG. 12.

FIG. 14 is another top front perspective view of the configuration of FIG. 12.

FIG. 15 is a bottom front perspective view of the configuration of FIG. 12.

FIG. 16 is a bottom rear perspective view of the configuration of FIG. 12.

FIG. 17 is a top plan view of the configuration of FIG. 12.

FIG. 18 is a bottom plan view of the configuration of FIG. 12.

(Continued)

FIG. 19 is a front elevation view of the configuration of FIG. 12.

FIG. 20 is a rear elevation view of the configuration of FIG. 12.

FIG. 21 is right elevation view of the configuration of FIG. 12; and,

FIG. 22 is left elevation view of the configuration of FIG. 12. The broken lines shown herein depict unclaimed portions of the electronic device, are for illustrative purposes and form no part of the claimed design.

1 Claim, 15 Drawing Sheets
